FIG. 2

UNITED STATES PATENT OFFICE

2,005,590

TELEPHONE SYSTEM

John Meszar, Bogota, N. J., assignor to Bell Telephone Laboratories, Incorporated, New York, N. Y., a corporation of New York

Application September 29, 1934, Serial No. 746,035

5 Claims. (Cl. 179—41)

This invention relates to toll telephone systems and more particularly to selective transfer systems whereby an "outward" operator may signal either one of two different operators over the same line circuit, for example, either a so-called "inward" or completing operator, or a "through" operator depending upon the nature and destination of the call.

In the well-known ringdown method of operating toll lines, it is the usual practice to have all the incoming line signals appear at the inward or completing operator's position and when "through" positions are provided, multiple the incoming lines to such positions. Line signals are also provided at such through positions but are not controlled by the outward operator, instead they are controlled from the inward position. Therefore, the inward operator receives all calls and if the destination of a call is such as to require the attention of the "through" operator, the inward operator "transfers" the call by performing an operation which actuates the line signal at the through position associated with the multiple appearance of the line on which the call is waiting. Observing this line signal the through operator connects with the line in the usual manner and extends it as desired.

The patent to R. S. Bailey et al. 1,860,446, dated May 31, 1932 discloses a straightforward toll line system employing alternating current, having a frequency within the voice range, for operating the calling and supervisory signal apparatus. In that system the initiation of a call at an outward position, results in transmitting current of a certain frequency over the line to the distant office where it causes apparatus to function to operate a call lamp and also to transmit an "answer-back" or "cut-off" signal to the outward or originating position. When this cut-off signal is received at the outward position, it immediately causes apparatus to function to stop the transmission of the "connect" signal current.

In the patent referred to a signal position only is shown at each end of the line. In case the position, (Fig. 5) which may be assumed to be an inward or completing position, is located at an office where the line is also multiplied to appear at a through operator's position, it is desirable, in order to eliminate delays caused by the inward operator answering and transferring calls requiring the attention of a through operator, to provide means whereby the outward op-

erator may selectively signal either the inward or through operator as desired.

An object of the invention is, therefore, to enable an outward operator to selectively signal either one of two different classes of operators over the same line. 5

A feature of the invention whereby the foregoing object is attained resides in the provision of means in connection with the system disclosed in the before referred to Bailey Patent 1,860,446 10 whereby the means normally responsive to the cut-off signal is made slow to operate thereby introducing a short delay in cutting off the connect signal from the line and by the provision of other means whereby the outward operator may 15 change the circuit connections to accelerate the operation of the cut-off apparatus to shorten the normal duration of the connect signal impulse sufficiently to cause apparatus at the distant office to function to prevent normal operation of 20 the line signals at the inward position and cause the line signals at the through position to operate instead.

The invention will be understood from the following description when read in connection with 25 the accompanying drawings:

Fig. 1 of which represents an outward operator's position and the portion of the line located thereat; and

Fig. 2 represents apparatus at the distant office 30 where the line is arranged to terminate at different positions, i. e., at an inward position and also at a through position.

It will be first assumed that the outward operator, Fig. 1, desires to obtain a connection 35 which would be handled by the inward or completing operator at the distant office. She will, therefore, insert the calling plug 4 of toll cord TC in jack 2 of the toll line L after having first operated the usual talking key 3 which causes 40 the obvious operation of relays 4 and 5. The operation of relay 5 in turn causes relay 7 to operate in a circuit which can be traced from a high resistance ground (not shown) on the sleeve of jack 8 with which the answering plug 9 of the 45 cord circuit has been previously connected, sleeve conductor of plug 9, operated contacts 10 of relay 5 and windings of relays 6 and 7 to battery. Relay 6 is marginal and does not operate under this condition. The operation of relay 50 7 caused the obvious operation of relay 11, which at its left-hand contacts completed the connection of the operator's telephone set OT across the talking conductors of the cord circuit by way of contacts 12 and 13 of relay 4 which was operated 55

in response to the actuation of the talking key 3. Another connection to said operators telephone circuit is made from ring conductor of plug 1, through lower operated make contacts of relay 4, 5 normally closed left-hand contacts of relay 38 to conductor 31 and from tip conductor of plug 1 through upper inner make contacts of relay 4, 10 operated left-hand contacts of relay 37 to conductor 39. Relay 37 operates as will be hereinexplained. Relay 41 in operating also closed a circuit traceable from battery through supervisory lamp 21, upper inner operated make contacts of relay 5, high resistance 33 to ground on right-hand operated contacts of relay 11. 15 Lamp 21 is not lighted under this condition.

It will now be observed that with plug 1 in jack 2, a source of battery potential 14 is connected to the sleeve conductor 15 of the toll line, which can be traced from battery 14, through 20 normally closed contacts of relay 16, windings of relay 17 and marginal relay 18, operated contacts 19 of relay 5, over sleeve conductors of plug 1 and jack 2 and conductor 15 to ground through the winding of sleeve relay 20. Relays 17, 18 25 and 20 operate in this circuit. Relay 17 operates through an obvious circuit relay 37. Relay 18 in operating connects a low resistance 35 to ground and relay 37 connects to ground a high resistance 36. These two resistances in multiple 30 are also connected through the lower, inner operated make contacts of relay 5 to battery through calling supervisory lamp 32, which lights. Marginal relay 18 operated in the circuit above traced due to the low resistance condition of the winding 35 of sleeve relay 20, which winding consists of separate low resistance and high resistance sections. For descriptive purposes only a single winding is shown in the accompanying sketch and the circuit details whereby the effective 40 resistance of the winding is changed from high to low are omitted as this method of obtaining supervision on toll lines is well-known in the art and is disclosed in above mentioned patent to R. S. Bailey et al. 1,860,446, Fig. 1, as shown by the functioning of relay 102 in said patent. 45 Relay 20 in operating operates relay 21 which operates through an obvious circuit line busy signal 28. Relay 20 also operates relay 26 through a circuit traceable from ground on the operated contacts of relay 20, through the left-hand normally closed contacts of relay 22, outer right-hand normally closed contacts of relay 25 and winding of relay 26 to battery. Relay 26 locks to ground on the contacts of relay 24 over a 50 circuit traceable from battery through the winding of relay 26, left-hand and right-hand outer operated contacts of relay 26, through normally closed contacts of relay 24 to ground. Relay 26 in operating operates relay 25 through a circuit 55 traceable from battery through right-hand winding of relay 25, right-hand inner and outer operated contacts of relay 26 to ground on normally closed contacts of relay 24. In operating, relay 25 operates through an obvious circuit, relay 97 60 which disconnects line conductors 35 and 37 from conductors 36 and 38, respectively, and connects them to a source 39 of voice frequency current of 1400 cycles modulated at a 20 cycle rate. This circuit is traceable from 1400/20 cycle current source 38 through right-hand inner operated make contacts of relay 25, through lower operated make contacts of relay 37 to conductor 31, thence through resistance 33 and in multiple with coil 39 of the directional selection circuit arrangement 96 to conductor 40 of toll line L. Return- 75

ing over conductor 41, the circuit is further traced through coil 34 and resistance 32 in multiple, over conductor 35, through upper operated make contacts of relay 97 and the left-hand outer operated make contacts of relay 25 to point of beginning at source 39 of the 1400/20 cycle 5

The aforesaid direction selection circuit arrangement is disclosed and claimed in the patent to George Crismon 1,755,243 issued April 22, 1930 and, as it forms no part of the present invention, it is deemed sufficient to state that this arrangement is constructed and arranged as to prevent any portion of the voice frequency current from source 39 applied to the line L by relay 37 from flowing over leads 42 and 43 into the receiving circuit RC1 while at the same time diverting voice frequency signals received over the line from the other end and transmitting them without attenuation to the signal receiving circuit RC1. It will therefore be understood that the 1400/20 cycle signal, transmitted over the line as a calling or connect signal is not impressed on the signal receiving circuit RC1 but that signals transmitted from the distant 20 end, are shunted into receiving circuit RC1 to cause the functioning of apparatus as will be hereinafter described.

When the 1400/20 cycle current is transmitted over conductors 40 and 41 of the toll line to the distant office it enters over conductors 93 and 99 of Fig. 2 and is transmitted through coils 44 and 45 of the directional selection circuit arrangement 46, (which is similar to that at the outgoing end of the toll line) over conductors 47 and 48 to receiving circuit RC2. The incoming 1400/20 cycle signal is here detected by detector vacuum tube 49 and amplified by vacuum tube 50. The 20 cycle output of tube 50 is transmitted through transformer 53 to the winding of polarized relay 52, the armature of which is caused to vibrate at a 20 cycle rate. This causes the full wave rectifier R1, which is an arrangement well-known in the art and need not be described here, to deliver a unidirectional current to relay 51 which operates. Relay 51 in operating operates, through an obvious circuit, relay 54 which in turn operates relay 55, thereby operating relay 56 and starting the operation of slow operating timing relay 57, through a circuit traceable from battery through resistance 58, left-hand operated make contacts of relay 55, resistance 59 to ground through the winding of relay 57. The operating circuit for relay 55 is traced from ground on the operated contacts of relay 54 through the winding of relay 55 to battery and for relay 56 from ground through the winding of relay 56, right-hand inner operated make contacts of relay 55 to battery. Relay 55 in operating also operates relay 84 through a circuit that may be traced from battery through the winding of relay 84, right-hand outer operated make contacts of relay 55 to ground. Relay 84 operates relay 61 through an obvious circuit and connects 1000/30 cycle current to the toll line over a circuit that may be traced from source 64 of 1000/30 cycle current through right-hand outer operated contacts of relay 84, and upper operated make contacts of relay 61 to conductor 62 and from source 64 through left-hand operated contacts of relay 84, and lower operated make contacts of relay 61 to conductor 63. From conductors 62 and 63 the 1000/30 cycle current passes through the directional selection circuit arrangement 46 70 75 80 85 90 95 100 105 110 115 120 125 130 135 140 145 150 155 160 165 170 175 including resistances 65 and 66 to toll line conductors 98 and 99. No current from source 64 passes into the receiving circuit RC2. From conductors 98 and 99 the 1000/30 cycle current passes over the toll line and conductors 40 and 41 at the originating end (Fig. 1), through the directional selection circuit arrangement 90 and over conductors 42 and 43 into receiving circuit RC1 which is similar to receiving circuit RC2 previously described with the exception that this circuit is tuned to respond to 1000/30 cycle current. Relay 67 accordingly operates and operates relay 23 through an obvious circuit. Relay 23 in operating starts the operation of slow operating timing relay 27 through a circuit that may be traced from battery 68 through resistance 69, right-hand inner operated contacts of relay 23 and winding of relay 27 to ground. Relay 23 also closes a circuit for operating relay 22, which may be traced from battery on the operated inner make contacts of relay 21, through winding of relay 22 to ground on the left-hand operated make contacts of relay 23. Relay 22 locks to ground through an obvious circuit. After an interval of about 0.6 second relay 27 operates through the circuit hereinbefore traced and operates relay 24 through a circuit traceable from battery on the contacts of relay 27, through winding of relay 24 to ground on the right-hand operated outer contacts of relay 23. Relay 24 in operating disconnects the holding ground for relays 25 and 26 which release. Relay 25 in releasing disconnects the source 30 of 1400/20 cycle signaling current from the leads connected to the front contacts of relay 97 and also opens an obvious circuit through the winding of relay 97, which releases and reconnects conductors 35 and 37 to conductors, 36 and 38 respectively.

As a result of the above described circuit action the "connect" signaling current of 1400/20 cycles from source 30 was not disconnected until after the operation of slow-to-operate relay 27. During this delay interval from the time the 1400/20 cycle current is sent out until said slow operate relay 27 operates, which interval can be conveniently adjusted for approximately one second, slow operate relay 57 of Fig. 2 at the incoming end has had time to operate and cause the operation of relay 70 through a circuit traceable from battery on the operated contacts of relay 57 through the winding of relay 70 to ground on the operated contacts of relay 54. Relay 70 in operating operates relay 71 through a circuit traced from battery on the operated contacts of relay 70 through the lower winding of relay 71 to ground on the normally closed lower contacts of relay 72. Relay 71 in operating lights the cord circuit lamp 73 of the cord circuit IC at the inward toll position, through a circuit traceable from battery on the lower outside operated contacts of relay 71, through the lower closed contacts of relay 74 and lamp 72 to ground. Relay 71 in operating also closes an obvious circuit through the winding of relay 74 to the sleeve conductor of plug 75 of inward cord circuit IC and locks through a circuit traceable from battery on the right-hand closed contacts of relay 76 through upper inner operated contacts and upper winding of relay 71 to ground on the lower closed contacts of relay 72. Relay 71 in operating also removes ground on its upper outside contacts from the lower winding of relay 72, thereby preventing the operation of relay 12 and the false lighting of lamp 96 as the through po-

sition after the disconnection of the 1400/20 cycle current at the outgoing toll office as hereinbefore described causes the release of relay 51 of receiving circuit RC2. The release of relay 51 causes the subsequent release of relays 54, 55, 70, 57, 84 and 61. Relays 84 and 61 in releasing disconnect the source 64 of "answer-back" 1000/30 cycle current from the toll line. Relay 61 reconnects line conductors 62 and 80 and 63 and 78, thereby restoring the normal continuity of the 10 conversational path.

In response to the call coming in on inward cord circuit IC telephone circuit OT2 is connected to conductors 77 and 78, thereby enabling the inward operator to converse over the toll line 15 with the originating operator. The circuit details of said telephone circuit OT2, with the particular circuit means that may be used for effecting the connection are well-known in the art and need not be shown here. After obtaining the 20 number of the called line, the inward operator completes the connection by plugging into the jack of a trunk not shown over which connection with the line of the called subscriber may be made. When the inward operator inserts 25 plug 75 into said trunk jack ground on the sleeve conductor operates relay 74 through the lower operated inner contacts of relay 71. Relay 74 in operating extinguishes lamp 73 by opening at its lower outside contacts the energizing circuit 30 for said lamp hereinbefore traced and also connects conductors 77 and 78 through its upper contacts and lower inside contacts to the tip and ring conductors of plug 75, thereby extending the talking connection from the originating 35 office to the trunk (not shown) leading to the office at which the line of the called subscriber terminates. The trunk operator at the terminating office now completes the connection to the called line according to well-known traffic 40 methods and supervision is transmitted to the originating office using the source 64 of 1000/30 cycle current as the means of transmission for controlling the resistance of sleeve relay 20 at the originating end as hereinbefore explained. 45 The circuit details required for establishing the final connection to the called line and for supervision are not shown since these are not a part of this invention. Bailey Patent 1,860,446 aforementioned discloses circuit details illustrative of 50 a method that may be used.

When the subscriber at each end of the connection hereinbefore described disconnects, the grounded resistance connected to the sleeve conductors of jacks 2 or 8 is changed from high to 55 low by circuit arrangements not shown, as stated hereinbefore, thereby causing the lighting of lamps 82 and 81 as disconnect signals. In the case of lamp 81 low resistance ground is effective through the upper normally closed contacts 60 of relay 5, if relay 5 is not operated at the moment or disconnection. If relay 5 is operated, then marginal relay 6 operates through the circuit hereinbefore traced for operating relay 7. Relay 6 in operating connects low resistance 100 in multiple with high resistance 83, and these two resistances together cause the lighting of lamp 81 through the upper inner operated make contacts of relay 5. In the case of lamp 82, if relay 5 is normal at the time of disconnection, the low resistance of sleeve relay 20 at this time is effective to cause the lighting of lamp 82 through the lower normally closed contacts of relay 5. If relay 5 is operated at the time of disconnection then marginal relay 18 operates through the circuit here- 70 75

inbefore traced for operating relay 17. Relay 18 in operating connects low resistance 85 in multiple with high resistance 86 and these two resistances together cause the lighting of lamp 82 through 5 the lower inner operated make contacts of relay 5. When the originating operator observes the lighted condition of lamps 81 and 82, plugs 9 and 1 are withdrawn from jacks 3 and 2 respectively which extinguishes lamps 81 and 82. Sleeve relay 28 also releases, releasing thereby relays 21 and 22 and restoring busy signal 28 to normal. At the time the disconnect signals are received, if talking key 3 is operated, and likewise relays 4 and 5, sleeve controlled relays 6, 7, 11, 18, 17 10 and 87 also release when the plugs are withdrawn. All apparatus at the originating end is now restored to normal. At the terminating end of the connection, relay 76 functions when a disconnect signal is received and opens the locking circuits 15 for relays 58 and 71 which release. Relay 71 in releasing, releases relay 74. The circuit arrangement for the release signal and for relay 76 are not shown, as these details are well-known, are not a part of the invention and are not required 20 for its description. When the inward operator removes plug 75 from the trunk jack (not shown) all apparatus is restored to normal.

The description hereinbefore given was for a call requiring the attention of the operator at 25 the inward position of the toll switchboard. The operation of the invention for a call requiring the attention of the operator at the through position will now be given.

In response to the line signal (not shown) the 30 operator inserts plug 9 into jack 3 and then operates the "talk" key 3 which connects the operator's telephone circuit OT to the talking conductors as hereinbefore described in connection with an inward call. After ascertaining that a connection requiring the attention of the through operator at the distant office is required the operator actuates "through" key 68 and inserts plug 1 into jack 2. Relays 4 and 5 function as hereinbefore described and likewise do relays 6, 7 and 11 with lamp 81 and associated resistances 83 and 88. The actuation of key 68 operates relay 16 over a circuit traceable from ground on key 68, through winding of relay 16 to battery on the right-hand normally closed contacts of relay 88. 35 Relay 16 locks to ground through its left-hand inner contacts, disconnects battery on its right-hand contacts from the winding of relay 17 and operates relay 88 through a circuit that may be traced from battery through the left-hand outer contacts of relay 16, winding of relay 88, lower inner operated make contacts of relay 4, over ring conductors of plug 1 and jack 2, lower winding of retardation coil 31, left-hand winding of relay 23, left-hand normally closed contacts of relay 23 40 to ground. Relay 88 in operating locks to battery on its right-hand inner make contacts, disconnects from battery on its right-hand normally closed contacts the winding of relay 16 which releases and also disconnects at its left-hand contacts conductor 91 from conductor 29 thereby separating temporarily the ring conductors of the two ends of the cord circuit TC to avoid the possible shunting effect from the calling line. Relay 25 also operates in the circuit hereinbefore 45 traced for the operation of relay 88 and operates relay 97 connecting thereby source 30 of 1400/20 cycle current to the toll line as hereinbefore described. When relay 16 releases it disconnects battery at its left-hand outer contacts from the winding of relay 88 and reconnects battery on its 50 right-hand normally closed contacts to the winding of relay 17, thereby operating relays 17, 18 and 20 over the circuit hereinbefore traced in connection with the description of an inward call. Relays 21 and 87 and busy signal 28 also operate. 55 The 1400/20 cycle current passing over the toll line operates relay 51 of receiving circuit RC2 at the distant toll office which causes 1000/30 cycle current to be sent back to the originating end as hereinbefore described to operate relay 67 of 10 receiving circuit RC1. Relay 67 operates relay 23 which opens at its left-hand normally closed contacts the operating circuit of relay 25, and the holding circuit of relay 88 hereinbefore traced. Relay 88 releases, reconnecting conductors 29 and 50 15 31. Relay 25 also releases, releasing relay 97, disconnecting thereby the source 30 of 1400/20 cycle current from the toll line and causing the release of relay 51 at the terminating end. Relay 51 in releasing, releases relays 54 and 55. Relay 55 in 20 releasing opens the operating circuit for slow operate relay 57, before it has had sufficient time to operate and also closes a circuit for operating relay 72 which is traced from ground on the normally closed upper contacts of relay 71 through 25 lower winding of relay 72, right-hand inner back contacts of relay 55, operated contacts of relay 56 and right-hand normally closed contacts of relay 76 to battery. Relay 72 in operating closes a circuit for lighting lamp 96 of through cord 30 circuit THC which may be traced from battery through the upper inner operated contacts of relay 72, lower normally closed contacts of relay 94 and lamp 96 to ground. In response to this signal, telephone circuit OT1 is connected by circuit means not shown to conductors 79 and 80, thereby enabling the through toll operator to obtain information for completing the connection. When this is obtained, plug 95 is inserted in the 35 jack of the circuit (not shown) leading to the line of the called subscriber. Relay 94 now operates through a circuit traced from battery through the winding of relay 94, lower inner operated contacts of relay 72 to ground on the sleeve conductors of plug 95 and said jack hereinbefore mentioned. Relay 94 in operating opens the circuit at its lower normally closed contacts through lamp 96, hereinbefore traced, extinguishing said lamp and also connects through its make contacts conductors 79 and 80 to the tip and ring conductors of plug 95. Relay 72 also locks through its upper outer make contacts to ground on the left-hand normally closed contacts of relay 16 and disconnects ground at its lower normally closed contacts from the windings of relay 71. The connection to the line of the called subscriber is now completed over circuits not shown and which are not a part of this invention. 45

After the subscribers disconnect, in response to the disconnect signals at the originating end 60 (Fig. 1) all apparatus thereat is restored to normal as explained in connection with the description for a call to the inward operator. At the completing end (Fig. 2) relay 72 releases, releasing relay 94, when release relay 76 functions and 65 all other relays are restored to normal as explained hereinbefore in connection with the description for an inward call.

What is claimed is:

1. In a signaling system, an outward operator's 70 position, a line extending therefrom and terminating at a plurality of different operators' positions, line signals at each of said distant positions, a source of alternating signaling current at each end of the line, means at the outward 75

- position for connecting its associated source of current to the line as a connect signal, means at the other end of the line responsive to said transmitted connect signal to operate the line signal at one of said positions and to connect the signal current source thereat to the line as an answer-back signal, means at the outward position responsive to said answer-back signal to disconnect said connect signal current from the line, and operator controlled means at the outward position adapted to accelerate disconnection of the connect signal in response to the answer-back signal whereby the connect signal is shortened, and means at the distant end of the line responsive to said shorter connect signal impulse to prevent the line signal from operating at said one position and to operate the line signal at the other position.
2. In a voice frequency signaling system, a line, an outward operator's position at one end of the line, two different positions at the other end of the line, an operator's connecting circuit and a source of alternating current at the outward position, a line signal at each of the different positions at the other end of the line, and means for connecting said current source to the line responsive to association of said connecting circuit with the line, means at the other end of the line responsive to said line current for operating a predetermined one of said line signals and for causing disconnection of said source at the outward position, selective means at the outward position for accelerating the disconnection of said source by a predetermined length of time, and means at the other end of the line responsive to a predetermined shorter duration of the line current to prevent operation of the first line signal and to cause operation of the other line signal.
3. In a signaling system, a transmitting station, a receiving station, a line interconnecting said stations, a source of alternating signaling current of a predetermined characteristic at the transmitting station, a source of alternating signaling current of a different characteristic at the receiving station, a plurality of signals at the receiving station, means at the receiving station responsive to the connection to the line at the transmitting station of said signal current to cause the connection to the line at the receiving station of the associated source of signaling current thereat and to cause the operation of a predetermined one of said signals and to prevent the operation of the other of said signals, means at the transmitting station responsive to the connection to the line at the receiving station of the source of signaling current thereat to cause the disconnection of the source of signaling current at the transmitting station, means at the receiving station responsive to the disconnection of signaling current at the transmitting station to cause the disconnection of the signaling current at the receiving station, and means at the transmitting station for accelerating the disconnection of the source of signaling current thereat whereby the second mentioned of said signals is operated, and the operation of the first mentioned signal is prevented.
4. In a signaling system, a line, an operator's position and a connecting circuit at the outward end of the line, two different operators' positions at the inward end of the line, a source of alternating signaling current at the outward end of the line of a certain characteristic, a source of alternating signaling current of a different characteristic at the inward end of the line, line signals at each of the positions at the inward end of the line, a receiving circuit at the outward end of the line, a receiving circuit at the inward end of the line, means responsive to the association of said connecting circuit with the line for connecting to the line at the outward end said source of signaling current thereat whereby said receiving circuit at the inward end is caused to function, means at the inward end responsive to the functioning of the receiving circuit thereat whereby the said source of signaling current at the inward end is connected to the line thereat and a predetermined one of said line signals is caused to operate, the operation of the other of said line signals is prevented and the receiving circuit at the outward end is caused to function, means at the outward end of the line responsive to the functioning of the receiving circuit thereat to cause the disconnection of the signaling current at said outward end, means at the inward end responsive to the disconnection of said signaling current at the outward end to cause the disconnection of said signaling current at the inward end, operator controlled means at the outward end for accelerating the disconnection of said signaling current thereat in response to the connection of said signaling current at the inward end to prevent the operation of the first mentioned line signal and to operate the second mentioned line signal.
5. In a voice frequency signaling system, a line, an operator's position and connecting circuit at the outward end of the line, two different operators' positions at the inward end of the line, a source of modulated voice frequency signaling current at the outward end of the line of a certain characteristic, a source of modulated voice frequency signaling current of a different characteristic at the inward end of the line, a line signal at each of said two positions at the inward end of the line, receiving circuits at the outward and inward ends of the line each tuned to detect and amplify modulated voice frequency signaling current of a predetermined characteristic incoming over the line, means for connecting to the line at the outward end said source of modulated voice frequency signaling current thereat responsive to the association of said connecting circuit with the line whereby said receiving circuit at the inward end is caused to function, means responsive to the functioning of said receiving circuit at the inward end whereby said source of voice signaling current thereat is connected to the line, the receiving circuit at the outward end is caused to function, and a predetermined one of said line signals is operated and the operation of the other signal is prevented, means responsive to the functioning of the receiving circuit at the outward end whereby said source of voice frequency signaling current thereat is disconnected, means at the inward end responsive to the said disconnection of the voice frequency current at the outward end, whereby the voice frequency current at the inward end is disconnected, and operator controlled means at the outward end whereby the disconnection of the voice frequency signaling current thereat is accelerated, and means at the inward end whereby said accelerated disconnection of the voice frequency current at the outward end causes the operation of said second mentioned signal and prevents the operation of said first mentioned signal.
